UNITED STATES PATENT OFFICE.

HENRY THOMAS JOHN GILBERT, OF ROYALTON, MINNESOTA, ASSIGNOR
OF ONE-FOURTH TO CHARLES W. BOUCK, OF SAME PLACE.

MAIL-BAG FASTENER.

SPECIFICATION forming part of Letters Patent No. 557,663, dated April 7, 1896.

Application filed July 29, 1895. Serial No. 557,443. (No model.)

To all whom it may concern:

Be it known that I, HENRY THOMAS JOHN GILBERT, a citizen of the United States, residing at Royalton, in the county of Morrison 5 and State of Minnesota, have invented a new and useful Mail-Bag Fastener, of which the following is a specification.

This invention relates to an improvement in mail-bags, and has special reference to the 10 means for locking or fastening the same in order to prevent access thereto while *en route*.

The object of the present invention is to provide a simple and efficient construction of fastening device for mail-pouches which 15 may be operated with the greatest possible rapidity and which will effectively close and fasten the mouth of the pouch.

The primary object of the invention is to provide the mouth of the mail pouch or bag 20 with an overlapping portion or flap carrying a series of swiveled eyebolts, the latter being adapted to pass through apertures in the bag, and to employ in connection therewith a flexible chain comprising a series of links in the 25 form of sheet-metal plates hinged together and formed with T-shaped slots, which embrace the shanks of the eyebolts and prevent the withdrawal of the heads of said bolts when in locked position.

30 A further object of the invention is to provide, in connection with such flexible chain, a novel form of automatic lock which will set itself upon simply sliding said chain in the proper direction.

35 In order to accomplish the objects above enumerated, the invention consists in certain novel features and details of construction and arrangement of parts, as hereinafter fully described, illustrated in the drawings, and 40 finally pointed out in the claims.

In the accompanying drawings, Figure 1 is a perspective view of a sufficient portion of a mail-pouch to illustrate the application of the present improvements. Fig. 2 is a horizontal 45 section through the mouth of the bag. Fig. 3 is a plan view of the flexible locking-chain. Fig. 4 is an elevation of the lock-case, a portion of the adjacent plate being broken away to show the interior construction.

50 Similar numerals of reference designate

corresponding parts in the several figures of the drawings.

Referring to the drawings, 1 designates a mail-pouch of the ordinary description having an open upper end, which is reinforced 55 upon the exterior by means of a collar 2, of leather or any preferred material.

3 designates a flap, which is composed of leather and riveted to the mouth of the bag upon one side thereof. Between this flap and 60 the bag proper is interposed a spacing-strip 4, also preferably of leather, said spacing-strip being provided with a large rectangular slot extending nearly the entire length thereof and a distance almost equal to the width 65 of the mail-bag at its mouth, such spacing-strip being held in place by means of the rivets which secure the flap in place.

By means of the construction just described a longitudinal passage 5 is formed, in which 70 may be slidably arranged the flexible locking-chain, to be hereinafter described.

6 designates a series of eyebolts, which have a swiveled connection with the overlapping portion of the flap 3, said bolts being adapted, 75 when the flap is closed, to pass through vertically-disposed slots 7 in the opposite portions of the mouth of the bag and in transverse alinement with each other.

8 designates a series of slotted wear-plates, 80 corresponding in number to the eyebolts and adapted to receive the eyes of said bolts and to form bearing plates or supports therefor when the heads of said bolts are projected through the transversely-alining slots in the 85 bag.

Arranged within the passage 5 above described is a flexible chain, the same comprising a longitudinal series of sheet-metal plates 9 and 10. The plates 9 each are formed with a 90 T-shaped slot, as indicated at 11, said slot consisting of a vertical portion and a horizontal portion at right angles thereto. Each pair of slotted plates 9 is connected by an intermediate plate 10, said plates being united by means 95 of the usual alternating perforated ears and pintles, the same as in an ordinary hinge. These T-shaped slots are so disposed that they will exactly register with the transversely-alining slots in the mouth of the mail-bag 100.

and through which the eyebolts pass. Thus it will be seen that when the vertical portions of the slots 11 register with the slots in the mouth of the mail-bag it is possible to insert 5 or withdraw the heads of the eyebolts; but when the flexible chain is moved longitudinally the horizontal portions of the slots 11 will be coincident with the slots in the mail-bag, thereby rendering it impossible to withdraw 10 the heads of said bolts. The flexible chain may be moved longitudinally by means of a pair of knobs 12, which are connected rigidly to said chain and have their shanks extended through longitudinally-elongated 15 slots 13 in plates 14, riveted to the mouth of the bag, as shown in Fig. 1.

At a suitable point an opening 15 is formed through the base portion or collar of the flap 3 for the reception of a lock-case, (indicated 20 at 16.) This lock-case may be made in any desired shape, comprising, essentially, a series of perforated ears, by which it may be riveted in place, and a raised portion forming a receptacle for the locking mechanism. The base 25 of the lock-case is depressed, as indicated at 17 in Fig. 2, and has rotatably mounted between the depressed and raised portions thereof a rotatable disk 18, the upper surface of which is inclined or cam-faced and underlies a flat spring 19 secured at one end in any 30 convenient manner within the lock-case rigidly and resting at its free end in engagement with a series of ratchet-teeth 20 formed upon the adjacent side face of one of the slotted 35 plates 9 above described. The disk 18 is also provided with a slot or slots providing for the insertion of one or more wings on a key 21. By inserting the key 21 through a corresponding opening through the lock-case and into 40 the disk 18 the latter may be turned in such manner as to cause it, by reason of its cam-face, to force the spring 19 out of engagement with the ratchet-teeth on the flexible chain. This will permit the chain to be moved longitudinally for unlocking the bag.

22 indicates a reinforcing plate or brace, which is secured to the inside of the mouth of the bag adjacent to the lock for preventing the bulging of the mouth of the bag at 50 such point and defeating the proper working of the lock. In order to prevent the accidental rotation of the disk 18, a knob or projection 23 is formed upon the periphery of said disk, which when the parts are in locked position strikes against a stop 24 and catches within a depression or offset 25 in a horizontally-disposed spring 26 in the manner illustrated in Fig. 4.

27 indicates an inwardly-extending tongue 60 or lip for preventing the lifting of the operative end of the spring 19 through the adjacent slot for the reception of one of the eyebolts, as shown in Fig. 2.

The improved fastening device hereinabove described is very simple in construction and will be found efficient in practice. By 65 reason of the flexibility of the locking-chain

the mouth of the pouch may be opened to any desired extent without danger of disarranging the locking mechanism. To open the 70 bag, the key 21 is inserted, as described, and given a quarter-turn. This lifts the locking-spring 19, after which the flexible chain is moved longitudinally and the eyebolts given a quarter-turn and withdrawn, as before explained. The key 21 is now turned backward and withdrawn from the lock-case, which allows the locking-spring to engage the ratchet-teeth on the chain. To close and lock the 75 bag, the eyebolts are inserted through their respective slots and given a quarter-turn, when by simply sliding the flexible chain by means of the knobs 12 the spring 19 engages the ratchet-teeth referred to and prevents the reverse movement of said chain. 80

It will be apparent that various changes in the form, proportion, and minor details of construction may be resorted to without departing from the spirit or sacrificing any of the advantages of this invention. 85

Having thus described the invention, what is claimed as new, and desired to be secured by Letters Patent, is—

1. In a mail bag or pouch, the combination with the mouth of the bag provided with transversely-alining openings, and the flap carrying turn-buttons having a swiveled connection therewith, the mouth of the bag being provided with an inclosed longitudinal passage, of a flexible chain slidingly mounted 95 within said passage and comprising a series of hinged plates slotted to receive and engage said turn-buttons, a series of ratchet-teeth formed on one of the plates, a locking-spring resting normally in engagement with said 100 ratchet-teeth, and provision for throwing the spring out of engagement with said teeth, substantially as specified. 105

2. In a mail bag or pouch, the combination with the mouth of the bag formed with a series 110 of transversely-alining slots, and a flap having a series of swiveled turn-buttons adapted to be passed through said slots, of a longitudinally-movable flexible chain mounted within a passage in the mouth of the bag and comprising 115 a plurality of sheet-metal plates hinged together, certain of which are formed with T-shaped slots each having a vertical portion adapted to register with the slots in the bag or pouch, and a horizontal portion adapted to 120 embrace the shank of an eyebolt, a series of ratchet-teeth formed upon the face of one of said plates, a locking-spring resting normally in engagement with said ratchet-teeth, and means for throwing said spring out of engagement with the teeth, substantially as and for the purpose specified. 125

3. In a mail bag or pouch, the combination with a longitudinally-movable locking bar or chain, of a locking-spring normally in engagement with a series of ratchet-teeth upon said bar or chain, a rotatable disk having an inclined active or working face for operating upon said spring to throw the latter out of en-

gagement with the teeth on the locking bar or chain, said disk being mounted within a suitable case and having a slot or recess for the reception of a suitable key, substantially as set forth.

4. In a mail bag or pouch, the combination with a longitudinally-movable locking bar or chain having a series of ratchet-teeth thereon, of a locking-spring resting normally in engagement with said teeth, a rotatable disk mounted within a suitable lock-case and formed with a cam-face adapted to operate upon said spring for the purpose stated, said disk being provided with a key-slot and with

a peripheral knob or projection, a fixed stop 15 coöperating with said knob or projection for limiting the movement of said disk, and a retaining-spring having a recess or offset adapted to engage with said knob or projection, substantially in the manner and for the purpose specified.

In testimony that I claim the foregoing as my own I have hereto affixed my signature in the presence of two witnesses.

HENRY THOMAS JOHN GILBERT.
